UNITED STATES PATENT OFFICE.

AUGUST SCHOEL AND ALBERT E. BAUM, OF WATERLOO, IOWA.

OILER.

1,096,796.

Specification of Letters Patent. Patented May 12, 1914.

Application filed September 6, 1912. Serial No. 718,876.

To all whom it may concern:

Be it known that we, AUGUST SCHOEL and ALBERT E. BAUM, citizens of the United States of America, and residents of Waterloo, in the county of Blackhawk, State of Iowa, have invented a new and Improved Oiler, of which the following is a full, clear, and exact description.

Our invention has for its object to provide an oiler, and one particularly well adapted for use on windmills, having a member adapted to be raised by a pitman on a windmill, and against the tension of a spring, this member being connected with a rotatable member by means for operating the latter, the rotatable member having operating means for pumping a lubricant to a rotatable cup, having a spout for supplying a plurality of conduits with the liquid, and there being also means by which the rotatable member will rotate the cup.

Additional objects of the invention will appear in the following complete specification, in which the preferred form of the invention is disclosed.

In the drawings similar characters of reference indicate corresponding parts in all the views, in which—

Figure 1 is a view showing a portion of a windmill to which our oiler is attached; Fig. 2 is a side elevation of Fig. 1; Fig. 3 is an enlarged sectional elevation of the oiler; Fig. 4 is a sectional view similar to that shown in Fig. 3 but with parts broken away to show the means for pumping the lubricant to the rotatable cup; Fig. 5 is a sectional fragmentary view of the oiler looking at the device from the rear; Fig. 6 is a side elevation of Fig. 4; Fig. 7 is a side elevation of Fig. 5; and Fig. 8 is a plan view of Fig. 3.

Most of the windmills which have been in use for several years are so badly worn that it is difficult to connect with them any of the oilers now in use in such a manner as will insure an even and certain feed of the lubricant at all times. This fault is entirely removed with our oiler, as it is operated by a member secured to the pitman of the windmill, and which, with the operation of the said windmill, will be raised periodically, to strike and raise a member of the oiler for operating the latter, the said member of the oiler being held yieldingly downward by a spring. As the pitman member and the oiler member may have extending horizontal

surfaces it will be seen that the oiler is certain to be operated with the reciprocation of the pitman. The position of the member secured to the pitman may be adjusted relatively to the pitman, and in this way the distance of the upward movement of the oiler member and the operation of the oiler may be regulated.

By referring to the drawings it will be seen that a casing 5 is mounted on a bracket 6, supported by a member 7 on the windmill 8. This casing 5 has a bottom 9, with an opening 10, a tube 11 being secured to this bottom 9, around the opening 10, the tube 11 also being secured in an opening in the top 13 of the casing 5. Extending through the opening 10 the tube 11 and the opening 13, there is a member 14, this member 14 having at its lower terminal 15, a horizontally extending member 16, there being a spring 17 which presses against the bottom 9 of the casing 5, and against the horizontally extending member 16, for holding the member 14 yieldingly downward. The upper portion of the member 14 is bent over at 12, and extends down through an opening in the top 13, of the casing, and also through a tube 18, the lower terminal 19 of this bent portion 12 having pivoted to it a pawl 20, which is adapted to engage the teeth 21 of a gear wheel 22, this gear wheel 22 being mounted to rotate on a stud 23, secured to a standard 24 within the casing 5. It will be seen that with this construction when the horizontally extending member 16 is engaged by the horizontally extending portion 25 of the member 26, which is carried by the pitman 27 of the windmill, it will be pushed upward, carrying with it the bent portion 12 and its terminal 19, which will move the pawl 20 upward, and in engagement with one of the teeth 21 to rotate the wheel 22. The wheel 22 is prevented from rotating when the pawl 20 is moved downward with the member 14 by the pawl 28, pivoted to the standard 24. Secured to the wheel 22 there is a cam 29, on which is mounted the pawl 30, the pawl 30 having an opening 31, in which the cam 29 is disposed. It will therefore be seen that with the rotary movement of the wheel 22, and its cam 29, the pawl 30 will be reciprocated, this pawl 30 engaging the teeth 33 of a wheel 34, mounted on an arm 35, extending from the standard 24. This wheel 34 rotates in only one direction, and it is prevented from rotating in the opposite di-

rection by means of the pawl 36, which engages its teeth 33, this pawl 36 being pivoted to the standard 24.

It will be seen that the wheel 22 will be 5 rotated intermittently by the reciprocating movement of the member 14, and it will also be seen that the wheel 34 will be rotated intermittently by the rotation of the wheel 22, and the pawl 30 mounted on the cam 29. 10 This wheel 34, which will have a very slow and intermittent movement relatively to the movement of the windmill, serves as a means for distributing the lubricant, which is contained within the casing 5. The lubricant 15 passes through a lateral opening 37, to the conduit 38, in the member 39. This conduit 38 has a terminal 40, through which is disposed a plunger 41, this plunger 41 extending through an opening 42, in an arm 43, 20 secured to the standard 24, the plunger being provided with a wing 44, which is adapted to be engaged and be raised by a pin 45, on one face of the wheel 34, the plunger 41 being held normally downward by the 25 spring 46, which engages the arm 43, at one end, and presses against the wing 44, at the other end. The conduit 38 has another upwardly extending terminal 47, in which is secured the lower terminal 48 of the lubricant 30 supply pipe 49, there being a check valve 50 in the said terminal 47 below the lower terminal 48 of the lubricant supply pipe. This lubricant supply pipe extends upward in a sleeve 51, which is mounted to 35 rotate in an opening 52, in the top 13 of the casing. The said sleeve 51 is connected with the cup 53, disposed above the top 13 of the casing. The lubricant supply pipe 49 not only passes through the sleeve 51, but 40 also through an opening 54 in the cup. The upper terminal of the lubricant supply pipe 49 is bent over at 55, so that it will feed the lubricant into the cup. To the sleeve 51 and below the top 13 of the casing there is 45 secured a horizontal ratchet member 56, with which engages a pawl 57, on an arm 58 of a lever 59, fulcrumed to the arm 60, which is secured to the standard 24, the other arm 53 of this lever 59 being engaged at intervals 50 by the pin 62, which projects from the wheel 34, this pin 62 projecting in a direction opposite to the direction in which the pin 45 projects from the said wheel 34. The horizontally disposed ratchet wheel 56 is held 55 yieldingly in position so that it will be operated by the pawl to the best advantage, by a spring 63, which is disposed around the sleeve 51, the upper terminal of this spring 63 pressing against the bottom of the top of 60 the end of the casing, and the lower end of this spring 63 pressing against the ratchet wheel 56. It will therefore be seen that with the rotation of the wheel 34, the pin 45 will at intervals raise the wing 44, and 65 with it the plunger 41, to permit the lubri-

cant to flow through the opening 37 into the conduit 38, and that when this plunger 41 is again moved down by the spring 56, the lubricant will be forced through the lubricant supply pipe 41, and its terminal 55, to the cup 53. It will also be seen that with the rotation of the wheel 32 the pin 62 will, at predetermined intervals, oscillate the lever 59, which will, by means of the pawl 57, rotate the ratchet wheel 56, a predetermined 70 distance, and with it the cup 53. This cup 53 has an elongated spout 64, which rotates with the cup, and is adapted to supply the lubricant to each of the plurality of conduits 65, which feed the lubricant to the 80 pipes 66, which lead to the several bearings and other parts of the windmill, which it is necessary to lubricate.

A spring 61 is provided for connecting the arm 61, of the lever 59, with the lug 68 85 on the standard 24, this spring serving to hold the lever 59 yieldingly in position, to be engaged by the pin 62 on the wheel 34. The member 26 is carried by the pitman 27 of the windmill by a clamp 69, which is secured to the pitman 27, and which has a cup member 70, and projecting therefrom a member 71, having a threaded opening 72, through which the member 26, which may be a rod, extends. This member 26 has its 90 lower terminal 73 threaded, this threaded terminal extending into the threaded opening 72. A nut 74 meshes with the threaded terminal 73 below the projection 71, to hold the member or rod 26 in position, after it 95 has been adjusted. It will be seen that this member 26 may be raised or lowered relatively to the pitman 27, and may be secured in this adjusted position by the nut 74. By 100 this means the distance of the movement of the member or rod 14 may be regulated. When the member or rod 14 moves a relatively long distance, it will, by means of the pawl 20, rotate the wheel 22 a greater distance at each upward movement of the member or rod 14, than will be the case when the member or rod 14 moves upward a relatively short distance. The oil cup 70 is 105 preferably filled with hair for receiving the lubricant from the lower terminal of one of the pipes 66, when the pitman is raised, the oil passing from this cup 70 through the pipe 75, to any cup or mechanism which 110 may be mounted on the pitman 27.

Having thus described our invention, we 115 claim as new, and desire to secure by Letters Patent:

1. In an oiler, a cup having an opening and adapted to rotate, a lubricant supply pipe disposed through the opening for supplying the cup with the lubricant, the cup having a spout, a plurality of conduits adapted to be fed by the spout, means for rotating the cup, a member having a conduit leading to the lubricant supply pipe, there being an 120

other opening in the member leading to the conduit, a plunger in the second-mentioned opening, there being a third opening in the member leading to the conduit between the first two openings, and adapted to be closed by the plunger, a check valve between the first-mentioned opening and the third opening, and means for reciprocating the plunger.

5 2. In an oiler, a reciprocating member, resilient means for holding the reciprocating member yieldingly in a predetermined position, a member normally spaced from and adapted to strike the reciprocating member for operating the latter, a cup adapted to rotate and having a spout, a plurality of conduits disposed around the cup, and adapted to be fed by the spout, and means for rotating the cup and for feeding 15 the cup with the lubricant operated by the reciprocating member.

20 3. In an oiler, a lubricant supply pipe, a cup having an opening in which a lubricant supply pipe is disposed, the cup being adapted to rotate around the supply pipe, and the lubricant supply pipe having its upper terminal bent over for supplying the cup with the lubricant, a spout on the cup, a plurality of conduits adapted to be fed by the spout, 25 and means for rotating the cup.

30 4. In an oiler, a plurality of conduits, a cup having an opening therethrough, and being provided with a spout for feeding a lubricant to the conduits, a lubricant supply pipe extending up through the opening in the cup and having its upper terminal bent over for feeding a lubricant to the cup, means for pumping a lubricant through 35 the lubricant supply pipe, and means for 40 rotating the cup on the lubricant supply pipe.

45 5. In an oiler, a plurality of conduits, a frame having an opening, a sleeve disposed for rotating in the opening, a cup secured to the sleeve and disposed above the frame, the cup having an opening registering with the sleeve, a ratchet member secured to the sleeve below the frame, and a lubricant supply pipe extending up through the openings, 50 with its upper terminal bent over for feeding a lubricant to the cup, a lever, a pawl on the lever for engaging the ratchet member, means for pumping the lubricant through the supply pipe, and means for 55 operating the lever and the first-mentioned means.

60 6. In an oiler, a plurality of conduits, a cup having an opening and being provided with a spout for feeding a lubricant to the conduits, the cup being adapted to be moved relatively to the conduits, a member provided with ratchet teeth and connected with the cup, a lever, a pawl on the lever for engaging the ratchet teeth, a lubricant supply 65 pipe extending through the opening in the

cup for supplying the cup with the lubricant, a member having a conduit with an opening at one end, and leading to the supply pipe, and with an opening at the other end, a plunger in the opening in the said other end, there being a lateral opening in the last-mentioned member leading to the conduit and adapted to be closed by the plunger, a rotatable member, and means in connection with the rotatable member for 70 operating the lever and the pump member.

7. In an oiler, a plurality of conduits, a cup having an opening and being provided with a spout for feeding a lubricant to the conduits, the cup being adapted to be moved 80 relatively to the conduits, a member provided with ratchet teeth and connected with the cup, a lever, a pawl on the lever for engaging the ratchet teeth, a lubricant supply pipe extending through the opening in the cup for supplying the cup with the lubricant, a member having a conduit with an opening at one end, and leading to the supply pipe, and with an opening at the other end, a plunger in the opening in the said other end, 85 there being a lateral opening in the last-mentioned member leading to the conduit and adapted to be closed by the plunger, a rotatable ratchet wheel, means in connection with the rotatable ratchet wheel for operating the lever and the plunger, a rotatable cam member, and a pawl mounted on the cam member and engaging the ratchet wheel for rotating the latter intermittently.

8. In an oiler, a plurality of conduits, a cup having an opening and being provided with a spout for feeding a lubricant to the conduits, the cup being adapted to be moved relatively to the conduits, a member provided with ratchet teeth and connected with the cup, a lever, a pawl on the lever for engaging the ratchet teeth, a lubricant supply pipe for extending through the opening in the cup for supplying the cup with the lubricant, a member having a conduit with an opening at one end, and leading to the supply pipe, and with an opening at the other end, a plunger in the opening in the said other end, there being a lateral opening in the last-mentioned member leading to the conduit and adapted to be closed by the plunger, a ratchet wheel, a second ratchet wheel having a cam, a pawl mounted on the cam, and engaging the first ratchet wheel for rotating the latter intermittently, a reciprocating member, and a pawl on the reciprocating member for rotating the second ratchet wheel intermittently and means actuated by the first ratchet wheel for reciprocating the plunger.

9. In an oiler, a plurality of conduits, a frame having an opening, a sleeve disposed for rotating in the opening, a cup secured to the sleeve and disposed above the frame, the cup having an opening registering with the

opening in the sleeve, a member secured to the sleeve below the frame, ratchet teeth on the upper surface of the member, means for holding the member spaced below the frame, 5 a lubricant supply pipe extending up through the openings with its upper terminal bent over for feeding lubricant to the cup, a lever, a pawl on the lever for engaging the ratchet teeth, a lubricant means for 10 pumping the lubricant up in the supply pipe,

and means for operating the lever and the first-mentioned means.

In testimony whereof we have signed our names to this specification.

AUGUST SCHOEL.
ALBERT E. BAUM.
